[57] **ABSTRACT**

Laundry detergent compositions of low phosphate content and high sodium silicate content, containing peroxygen compound and activator therefore in minor amount.

5 Claims, No Drawings

ACTIVATED PEROXYGEN DETERGENT

This invention relates to laundry detergent compositions which contain little or no phosphate builder and which are mixtures of organic sulfonate or sulfate detergents with sodium silicate in large amounts. Certain particularly useful compositions of this type are described in the following three copending applications of Paul S. Grand, all filed on Nov. 12, 1971: Ser. No. 198,454 (Sulfate Detergent Compositions) Ser. No. 198,455 (Sulfonate Detergent Compositions) and Ser. No. 198,456 (Detergent Compositions); and in the continuations-in-part of said applications (having the same titles) being filed on or about May 22, 1972. The entire disclosures of the aforesaid Grand applications are incorporated herein by reference.

These compositions are particularly suitable for use in such amounts that the concentration of sulfonate or sulfate detergent in the wash water is within the range of about 0.02 to about 0.1%. Similarly the concentration of sodium silicate in the wash water is generally within the range of about 0.02 to 0.1%, more preferably about 0.03 to 0.06%. The sodium silicate is preferably the principal builder in the composition and is preferably present in an amount which is at least two thirds the amount of sulfonate detergent. For a composition to be used in 0.15% concentration in the wash water the proportion of sodium silicate is generally above 20% and below 50%.

It has been found that excellent stain removal is attained when such laundry detergent compositions are employed with a peroxygen compound in minor amount with an activator for said peroxygen compound, which activator is a peracid precursor. The amount of peroxygen compound is generally within the range of amounts representing about 5 to 30 parts of active oxygen per million parts of the wash water, more preferably about 10 to 20 ppm of active oxygen based on the weight of wash water. For compositions to be used at 0.15% concentration in the wash water and containing sodium perborate tetrahydrate (having about 10% active oxygen), a 20 ppm concentration of active oxygen is supplied by the presence of about 15% (e.g., 13%) sodium perborate tetrahydrate in the composition.

The mol ratio of activator to active oxygen (of the peroxygen compound) is preferably at most about 1:1 particularly in view of the relatively high cost of the activators. It has been found that good results can be obtained, at correspondingly lower cost, when lower ratios are employed. Thus one may use such ratios as 1:2, 1:3, 1:4, 1:6, or 1:8 or even lower ratios, e.g., 1:20 or 1:60. These ratios also have the advantage, of being usable for the washing of wash loads containing colored fabrics, particularly when the acyl moiety of the activator is one which (like benzoyl or m-chlorobenzoyl) yields a peracid of such strength that it may tend to remove the dye from dyed fabrics (e.g., blue dyed cotton percale) when it is used in 1:1 mol ratio.

Activators which are peracid precursors, are well known in the art. They are described, for instance, in a series of articles by Gilbert in *Detergent Age*, June 1967 p. 18-20, July 1967 p. 30-33, August 1967 p. 26, 27 and 67, which explains that such compounds include esters, anhydrides and amides. A listing of some of the commonly known activators is also found in the U.S. Pat. No. to Woods 3,632,634. Other disclosures of suitable activators are found in Canadian Pat. No.

844,481 which describes such amides (N-acyl compounds) as the N-acyl azoles; U.S. Pat. No. 3,061,550 which describes certain acylated imides; British Pat. No. 907,376 describing certain N-acyl compounds such as tetraacetyl ethylenediamine, tetraacetyl methylenediamine, etc; published Swedish Pat. application No. 17880/68 describing acylated glycolurils such as tetraacetylglycoluril; and French Pat. No. 1,590,335, describing N-acyl compounds having a m-chlorobenzoyl acyl group.

Particularly useful activators are of the amide type, well known in the art (and discussed in the patents and publications cited above) which have a monovalent carboxylic acyl group directly attached to a nitrogen atom and which, as mentioned above, form peracids on reaction with the peroxy compound in solution. In the most common such compounds the acyl group is acetyl or benzoyl or substituted benzoyl. It is within the broader scope of this invention, however, to use other types of peracid-forming activators, e.g., esters of anhydrides, (e.g., p-sulfophenyl ethyl carbonate). Various examples of activators are also given in Gray U.S. Pat. No. 3,637,339 of Jan. 25, 1972.

Preferred peroxygen compounds are sodium perborate, tetrahydrate and sodium percarbonate (e.g., $\text{Na}_2\text{CO}_3 \cdot 1.5 \text{ H}_2\text{O}_2$).

It is within the broader scope of the invention to use other forms of sodium perborate, e.g., sodium perborate monohydrate, or other activatable peroxy compounds; such compounds, e.g., urea-hydrogen peroxide and other peroxyhydrates, are well known in the art. The cation of the peroxygen compounds need not be Na; it may be, for example, K, Ca, Mg or H.

The invention is illustrated by the following Examples. In these Examples, and in the rest of application as well, all proportions are by weight unless otherwise indicated.

EXAMPLE 1

The accompanying Table I gives results obtained (in three series of runs) in tests of various detergent compositions for their effectiveness in the removal of stain on 3 x 6 inch coffee-tea stained cotton fabrics of predetermined reflectance (Rd) values, in a 10 minute washing in a vessel (a Tergotometer) at a temperature of 120°F, followed by a 5 minute rinse in fresh water at 100°F, (after which the swatches are dried, the Rd values are again recorded on a Gardner Color Difference Meter, and the average ΔRd value is determined.) In each case the amount of water in the wash vessel is one liter, the total amount of each "Detergent" is 1500 mg (giving a concentration of 0.15%). The activator used is m-chlorobenzoyl dimethylhydantoin.

The "Silicate Detergent A" contains 18% sodium linear dodecybenzenesulfonate, 25% sodium silicate of $\text{Na}_2\text{O}:\text{SiO}_2$ mol ratio 1:2.35, 4% nonionic detergent ("Neodol 45-11"), 2% sodium carboxymethylcellulose, 6% soap, about 5% moisture and the balance sodium sulfate. The "Silicate Detergent B" is similar except that its content of sodium linear dodecybenzenesulfonate is 25% and its content of soap is 1%. The "High Phosphate (TPP) Detergent" contains 10% alkylbenzenesulfonate, 2% nonionic detergent, 2% soap, 33% freshly added pentasodium tripolyphosphate ("TPP") and the balance sodium sulfate and about 8% moisture. The "High Phosphate (pyro) Detergent" is

similar except that it contains 33% freshly added sodium pyrophosphate in place of the 33% TPP.

The 150 ppm hardness water and 300 ppm hardness water are prepared by adding calcium and magnesium salts in appropriate amounts to New Brunswick tap water. Hardness is in ppm calculated as calcium carbonate (e.g. 100 ppm is equivalent to 40 ppm of Ca^{++} ion).

New Brunswick tap water has a hardness of about 100 ppm calculated as calcium carbonate and a copper content of less than 1 ppm. A typical chemical analysis of the New Brunswick tap water is as follows, all figures (except pH) being in parts per million, unless otherwise indicated: total hardness 90, alkalinity 38, CO_2 8, pH 7.6, chlorine 1.0, iron 0.05, manganese 0.00, consumed oxygen 0.6, dissolved oxygen 15.0, chlorides 25, total solids 165, organic and volatile 40, mineral matter 125, free ammonia 0.048, albumoid ammonia 0.015, nitrates

5

The foregoing table indicates that despite a reduction in the proportion of activator (in a system containing about 15 ppm of active oxygen and water of conventional hardness) the silicate system still gives good bleaching.

EXAMPLE II

A test similar to that used in Example 1 (except that the washing time is 15 minutes) is carried out with the 10 seven compositions (a through g) tabulated below. The same compositions are also tested under the same conditions, using clean blue percale swatches in place of the coffee-tea stained swatches. The results are given in Table II. It will be apparent that the use of a 1:1 mol ratio of the m-chlorobenzoyl activator caused undesirable bleaching of the blue percale in the concentrations employed in this test.

TABLE II

	ΔR_d VALUES OBTAINED ON WASHING WITH						
	Amount (mg) present per liter of wash solution						
	a	b	c	d	e	f	g
Silicate Detergent A	1000	1000	1000	1000	1000	1000	1000

					III	as indicated at left

tions. The amounts of sodium silicate and sulfonate or sulfate detergent in the resulting composition will be greater than the amount of peroxygen compound; the ratio of the amount of sodium silicate to the amount of peroxygen compound ratio will generally be at least about 2:1 (e.g., about 2:1 to 4:1) and the ratio of the total amount of surface active detergent (including nonionic detergent and soap, for instance) to the amount of peroxygen compound will generally also be at least about 2:1 (e.g., about 2:1 to 4:1). The sodium silicate preferably has an $\text{Na}_2\text{O}:\text{SiO}_2$ ratio of about 1:2 to 1:3.

In some cases either the activator or peroxygen compound or both may be suitably encapsulated (e.g., by means of a polymeric coating) to improve the storage stability of the composition with respect to moisture and other influences.

The washing temperatures may be the same as those taught in the art for use with activated peroxygen compositions, e.g., below 160°F and usually above room temperature, e.g., 90° or 100°F to 150°F, such as 105° or 120° or 150°F.

It is understood that the foregoing detailed description is given merely by way of illustration and that variations may be made therein without departing from the spirit of the invention. The "Abstract" given above is merely for the convenience of technical searchers and is not to be given any weight with respect to the scope of the invention.

We claim:

1. Built laundry detergent composition consisting essentially of (a) water soluble anionic sulfonate or sulfate detergent, (b) sodium silicate as the principal builder salt, (c) a peroxygen compound and (d) an ac-

tivator for said peroxygen compound, said activator having a carboxylic acyl group, said peroxygen compound being one which reacts with said activator to form the corresponding percarboxylic acid on addition of said composition to the wash water, the ratio of c to d being from about 8:1 to 2:1 of the stoichiometric ratio for said reaction, the ratio $(a+b):c$ being at least 2:1 and the ratio $b:c$ being over 1:1, and wherein said sodium silicate has an $\text{Na}_2\text{O}:\text{SiO}_2$ ratio of about 1:2 to 1:3.

2. Composition as in claim 1 in which the peroxygen compound is sodium perborate or sodium percarbonate and the activator is one which reacts therewith to form a perbenzoic acid.

3. Composition as in claim 2 in which the activator is a m-chlorobenzoyl amide.

4. A composition as in claim 2 in which said $b:c$ ratio is at least 2:1.

5. Built laundry detergent composition consisting essentially of (a) water soluble sodium linear alkylbenzenesulfonate detergent, (b) sodium silicate as the principal builder salt, (c) a peroxygen compound and (d) m-chlorobenzoyl dimethylhydantoin as activator for said peroxygen compound, said peroxygen compound being one which reacts with said activator to form the corresponding percarboxylic acid on addition of said composition to the wash water, the ratio of c to d being from about 8:1 to 2:1 of the stoichiometric ratio for said reaction, the ratio $(a+b):c$ being at least 2:1 and the ratio $b:c$ being over 1:1 wherein said sodium silicate has an $\text{Na}_2\text{O}:\text{SiO}_2$ ratio of about 1:2 to 1:3, and said composition also containing nonionic detergent and sodium carboxymethylcellulose.
